INERTIA OPERATED PUMP

Filed Sept. 21, 1929

FIG. 1.

INVENTOR.
Theodore Earle

BY

FIG. 3.

Rolland S. Trott ATTORNEY.

UNITED STATES PATENT OFFICE

THEODORE EARLE, OF DENVER, COLORADO

INERTIA OPERATED PUMP

Application filed September 21, 1929. Serial No. 394,320.

My invention relates to gasoline gauges for automotive vehicles and the like and more especially to automatic inertia-operated pumps for use in connection therewith, 5 and is an improvement over the invention in indicating mechanisms, of my associate Harry B. Ross, whose application was filed Dec. 14th, 1928, the serial number being 326,138.

10 It has been found that the discharge valve of an air pump having an inertia-operated piston working in connection with a gasoline indicating mechanism, tends to stick tight to its seat after the pump has been 15 idle for even a few hours.

This is probably due to the slight oil, asphalt, or paraffin content of the gasoline acting as a cement to hold the valve on its seat after a certain amount of evaporation 20 has taken place.

Another reason for this trouble is that an inertia-operated piston pump that is properly proportioned to the duty of delivering air to the operating tube of an indicating 25 mechanism, does not produce a high delivery pressure.

It has also been found that the intake valve of such a pump tends to stick upon its seat, probably due to dirt, or to a cementing residue of evaporation as stated above, and also due to the fact that a properly proportioned inertia-operated pump does not produce a very high vacuum on the suction stroke.

30 The object of this invention is to provide an inertia-operated pump for use with an indicating mechanism, in which the discharge valve will be positively started from its seat by contact with the piston at the end of the down stroke thereof.

A further object is to provide an inertia-operated piston pump in which a port in the cylinder wall is uncovered during a part of the upward movement of the piston to allow the cylinder below the piston to be filled with air, and in which the port is covered and the air trapped in the cylinder during a part of the downward movement of the piston.

35 A further object is to provide an inertia-

operated piston pump in which a port in the cylinder is uncovered during a part of the downward movement of the piston to allow the cylinder above the piston to be filled with air to act as a cushion to quietly stop 55 the upward movement of the piston.

A further object is to provide an inertia-operated piston pump, which, because of the piston controlled intake and cushion supply port, and the piston started discharge valve, 60 is completely inertia-operated, whereby positive operation of the intake and discharge functions will take place, resulting in positive pumping of air.

The construction by which the above objects are attained is described more in detail below and is illustrated in the drawings in which;—Figure 1 is a fragmentary diagram showing my completely inertia-operated pump and the main parts of the construction of an indicating device with which it is associated.

Figure 2 is a fragmentary view showing a modified form of my pump.

Figure 3 shows a modified form of piston. 75 The cylinder 1 is provided with the tank-fitting flange 2, and is to be properly fitted to the gasoline tank 3, the joint between them being made leak-proof in any proper manner.

The cylinder 1 is also provided with the port 31, the piston-receiving bore 4, the locking pins 5, only one of which is shown, and the cap 6 provided with the locking slots 6', only one of which is shown.

80 The cap 6 is to be substantially air tight, not only to prevent loss of cushion for stopping the upward movement of the piston without metallic contact, but also to prevent dirt being sucked into the cylinder on the downward stroke of the piston.

The discharge tube 7 is soldered in an opening in the bottom of the cylinder 1, or is otherwise properly attached thereto, with the interior of the tube in communication 85 with the interior of the cylinder.

The bell 8 is properly attached to the lower end of the tube 7, the joint between them being leak-proof.

90 The operating tube 9 is properly attached 102

to the bell 8, with its lower end adjacent to the lower end of the bell, the joint between them being made leak-proof and the passage of the tube 9 through the flange 2 is also made leak-proof.

5 The operating tube 9, at its other end, is properly attached to any indicating mechanism such as shown at 11, which is constructed to register the amount of gasoline in the tank 3, and which is operated by the pressure in the tube 9, which pressure is maintained proportional to the height of the gasoline in the tank by the action of the pump.

10 The gasoline feed pipe 10 to the carburetor of the vehicle, has its lower end adjacent the bottom of the tank 3, and is properly attached to the bell 8 as a brace or support, and its passage through the flange 2 is made leak-proof.

15 The tube 7 is provided with a rolled in internal shoulder 12 against which is seated the brass washer 13, upon which is seated the lead washer 14.

20 The valve cage 15 is provided with the lower beveled end 16, the valve spring 17, the ball valve 18 and the valve seat 19.

25 The cage 15 is a close fit in the upper end of the tube 7 and is pressed therein and to a tight seat upon the lead washer 14.

30 The piston 20 is provided with the two cylinder fitting rings or shoulders 21 and 22, the shoulder 22 being provided with one or more slots therethrough such as at 23.

35 The piston 20 is also provided with the valve contact pin 24, and is resiliently supported by the spring 25.

40 The piston has considerable clearance with the walls of the bore 4 except at the shoulders 21 and 22, which are a close sliding fit in the bore 4.

45 Upon the upward movement of the piston 1, the port 31 is uncovered by the shoulder 21 and air passes in through the port 31 and down along the piston and through the slot 23 to relieve the partial vacuum under the piston formed by its upward movement.

50 Upon the same upward piston movement, air trapped above the piston as the shoulder 21 passes upwardly over the port 31, acts as a cushion to bring it quietly to rest and prevent its contact with the cylinder cover.

55 On the downward movement of the piston, the shoulder 21 covers the port 31, which position is shown in Figure 1, and further downward movement of the piston compresses the air thus trapped in the cylinder, and the downward movement with the piston of the shoulder 21 opens the port 31 in the cylinder above the shoulder 21 to supply cushion air to the cylinder above the piston.

60 As the piston moves downward it compresses the spring 25, and at or near the end of the downward stroke of the piston the contact pin 24 engages the ball valve 18 and

bumps it off the seat 19, thus positively opening the valve even if evaporation of gasoline has caused the cementing action mentioned above.

65 As the piston moves upward on the rebound, which is assisted by the spring 25, the spring 17 causes the ball 18 to again contact the seat 19, preventing the loss of air from the tube 7. The piston rebound is first checked and then stopped by the air 75 cushion above it.

70 It will be noted that the weight of the piston 1, the strength and length of the springs 25 and 17, and the positions of the shoulder 21, the port 31, and the cylinder cover, must all be so related and proportioned as to provide in a moving vehicle, the rebound-cushioned pumping action desired.

75 When this has been taken care of, it will be seen that the movements of the piston 85 will positively insure the pumping of air through the discharge valve to the tube 7, which is what is desired.

80 In the modified form shown in Figure 2, the piston 20' is provided with the shoulders 90 21' and 22' at its ends, and at its lower end is provided with a shallow counterbore for the reception and positioning of the end of the spring 25'.

85 The port 31' through the wall of the cylinder 1' is controlled by the shoulder 22', the shoulder 21' being provided with a slot 23' whereby air from the port 31' may pass into the cylinder above the piston to form the air cushion.

90 The cylinder 1' is closed by the cover 6'', properly attached to the flange 2''. The poppet valve 18'' seats against the seat 19'' and is held thereon resiliently by the spring 17'.

95 The lower end of the valve has an apertured or notched guide plate 18'', and the upper end 24' is formed to act as a contact pin which contacts with the piston 20' at or near the limit of its downward travel.

100 The final result of this construction is the same as with the construction shown in Figure 1. That is, the dimensions, construction, and proportions of parts are such as to positively pump air into the tube 7 110 by the upward and downward movement of the piston 20' in the cylinder 1', and to quietly cushion the piston on its upstrokes so that its operation will be noiseless.

115 The port 31', controlled by the shoulder 22' acts as the intake valve, and the contact of the piston 20' with the discharge valve on its downward stroke acts to positively start the opening of the valve even when it is stuck in place by the evaporation 125 of the volatile constituents of the gasoline.

120 In the piston construction shown in Figure 3, the piston 20'' is provided with the shoulders 21'' and 22'', and is also pro- 130

vided with the hole or channel 26 by which the air trapped under the shoulder 21" as the piston covers the cylinder port, may pass to the lower face of the piston and on 5 through the discharge valve.

As any competent mechanic will perceive, any other proper closure for the upper end of the cylinder may be used, and any other proper details of construction may be employed for the discharge valve and for the means of providing contact between the valve and the piston, so long as the final result is the positive operation of both inlet and discharge functions as well as piston 10 action, all of which is accomplished as a result of the use of the inertia of the spring-suspended piston.

It is also obvious that my positive acting inertia-operated pump may be combined 15 with any proper indicating mechanism and in any proper way, and the unit to be inserted in the gasoline tank may vary considerably as to details of construction without departing from the essence of my invention.

Therefore, I do not wish to be narrowly limited to the exact details of construction illustrated and described, but what I claim 20 as new, and desire to protect by Letters 25 Patent, is as follows:—

1. In an inertia-operated pump, the combination of a ported cylinder, a spring-held discharge valve in communication with the cylinder, a piston-supporting spring in the 25 cylinder, and an inertia-operated piston in the cylinder in contact with said spring and uncovering the cylinder port during a part of its up-stroke, and uncovering said port and engaging said valve during a portion of 40 its down-stroke.

2. In an inertia-operated pump to provide air under slight pressure for the gasoline indicating mechanism of an automotive vehicle, and to be operated by the movement of the vehicle over the inequalities 45 of the road, the combination of a ported cylinder, a spring-held discharge valve in communication with said cylinder and said indicating mechanism, a piston-supporting 50 spring in said cylinder, and an inertia-operated piston in the cylinder and resting upon the said spring, and in its movements in the cylinder covering and uncovering said port, and contacting with and opening said discharge valve.

3. In an inertia-operated pump, the combination of a cylinder having a bore and provided with a spring-held discharge valve in communication with said bore, a piston-supporting spring in said bore, a piston in 55 said bore having a pumping and a suction stroke therein and resting upon said spring and contacting with and opening said discharge valve near the end of its pumping stroke, the cylinder being provided with 60 means controlled by said piston to admit air

into said bore during a portion of its suction stroke.

4. In an inertia-operated pump, the combination of a cylinder having a bore, and a piston reciprocable in the cylinder, a spring 70 in the cylinder supporting the piston, the cylinder being provided with intake and discharge means controlled by the movement of the piston in said bore.

5. In an inertia-operated pump, the combination of a cylinder having a bore and a piston reciprocable in the cylinder and movable on its down stroke by its inertia alone, a spring in the cylinder supporting the piston and moving it upon its up stroke, the cylinder being provided with an intake port positioned to be covered by the piston on its delivery stroke and being provided with discharge means adapted to contact and be opened by said piston.

6. In an inertia-operated pump, the combination of a ported cylinder having a spring-held discharge valve and a piston-supporting spring, and a piston reciprocable in the cylinder and resting upon the spring 90 and reciprocable in the cylinder by its own inertia and the spring and by the bodily movement of the cylinder to control the port of the cylinder as an intake to the cylinder and to contact with the discharge valve and open same positively to insure discharge from the cylinder.

7. In an inertia-operated pump to provide air under slight pressure for the gasoline indicating mechanism of an automotive vehicle, and to be operated by the inequalities 100 of the road, the combination of a cylinder having a piston-controlled intake port in its wall, and a spring-held, piston-contacting discharge valve in communication with said indicating mechanism, a piston-supporting spring in the cylinder and a piston in the cylinder resting upon the spring and having relative movement with respect to the cylinder due to its inertia and the bodily movement of the cylinder, and controlling the intake port and by contact therewith starting the opening of the discharge valve.

8. In an inertia-operated pump adapted to provide air under slight pressure for the gasoline indicating mechanism of an automotive vehicle, and to be operated by the inequalities of the road, the combination of a cylinder provided with means for the intake and retention of air and with a spring-held, piston-contacting discharge valve in communication with said indicating mechanism, a piston-supporting spring in the cylinder and a piston in the cylinder resting upon the spring and having relative movement with respect to the cylinder due to its inertia and the bodily movement of the cylinder, and by contact therewith starting the opening of the discharge valve.

9. In an inertia-operated pump, the com-

bination of a ported cylinder, a spring-held discharge valve in communication with one end of the cylinder, a piston-supporting spring in the cylinder and an inertia-operated reciprocating, port-controlling piston in the cylinder and in contact with said spring and controlling said port to trap air and compress air in each end of the cylinder during each complete reciprocation, and engaging and opening said valve during a portion of its down stroke for the discharge of the air in the valve end of the cylinder.

10. In an inertia-operated pump to provide air under slight pressure for the gasoline indicating mechanism of an automotive vehicle, and to be operated by the movement of the vehicle over the inequalities of the road, the combination of a ported cylinder, a spring-held discharge valve in communication with one end of the cylinder and said indicating mechanism, a piston-supporting spring in said cylinder, and an inertia-operated reciprocating, port-controlling piston in the cylinder and resting upon the said spring, and by the control of said port trapping air and compressing air in each end of the cylinder during each complete reciprocation and contacting with and opening the said discharge valve during a portion of its down stroke.

11. In an inertia-operated pump, the combination of a cylinder having a head end and a valve end and having a bore and provided with a spring-held discharge valve in communication with the valve end of said cylinder, a piston-supporting spring in said bore, a piston in said bore having a delivery and a suction stroke as it reciprocates with respect to the cylinder and resting upon said spring, the cylinder being provided with means to admit air into the valve end of said bore during a portion of the suction stroke of the piston while compressing air trapped in the other end of the bore, and to admit air into the head end of the cylinder during a portion of the pumping stroke of the piston while compressing air in the valve end of the cylinder, the piston contacting with and opening the discharge valve prior to the completion of the pumping stroke.

12. In an inertia-operated pump, the combination of a cylinder having a head and a valve end and a bore, and a piston reciprocable in the cylinder and movable on its down stroke by its inertia alone, a spring in the cylinder supporting the piston, the cylinder being provided with an intake port communicating with both ends of the cylinder alternately as the piston reciprocates in the cylinder, and with discharge means at the valve end of the cylinder, the piston contacting with and opening said discharge means prior to the completion of the delivery stroke.

13. In an inertia-operated pump, the com-

bination of a closed cylinder having a bore, a piston having a cylinder fitting flange both sides of which communicate with the respective ends of the piston, reciprocable in the cylinder and moved on its downward stroke by its inertia alone, a spring in the cylinder supporting the piston, the cylinder being provided with intake port means in its walls controlled by said flange to feed air to both ends of the cylinder alternately as the piston reciprocates, and discharge means at one end of the cylinder adapted to contact with and be opened by said piston.

14. In an inertia-operated pump, the combination of a double ended ported cylinder having a spring-held discharge valve and a piston-supporting spring at one end, and a piston reciprocable in the cylinder and resting upon the spring and adapted to be reciprocated in the cylinder by its own inertia and the spring and by the bodily movement of the cylinder to control the port of the cylinder as an intake to both ends of the cylinder and to contact with the discharge valve and open same positively to insure discharge from the cylinder.

15. In an inertia-operated pump to provide air under slight pressure for the gasoline indicating mechanism of an automotive vehicle, and to be operated by the inequalities of the road, the combination of a double ended cylinder having a piston controlled port to both ends of the cylinder in its wall, and a spring-held, piston-contacting discharge valve in communication with said indicating mechanism, a piston-supporting spring in the cylinder and a piston in the cylinder resting upon the spring and having relative movement with respect to the cylinder due to its inertia and the bodily movement of the cylinder, and controlling the intake port to the cylinder ends and by contact therewith starting the opening of the discharge valve.

16. In an inertia-operated pump to provide air under slight pressure for the gasoline indicating mechanism of an automotive vehicle, and to be operated by the inequalities of the road, the combination of a double ended cylinder provided with means for the intake to and the retention of air in both ends thereof and with a spring-held, piston-contacting discharge valve in communication with said indicating mechanism, a piston supporting spring in the cylinder and a piston in the cylinder resting upon the spring and having relative movement with respect to the cylinder due to its inertia and the bodily movement of the cylinder, and by contact therewith starting the opening of the discharge valve.

In testimony whereof I affix my signature.
THEODORE EARLE.
